RACK WITH CONTENTS-SECURING MEANS

Jones S. Jordan, Chester Heights, Pa.

Application February 15, 1936, Serial No. 63,994

5 Claims. (Cl. 211—85)

The object of the invention is broadly to provide improvements in folding racks, but more especially in those types which are particularly adapted to display cans, boxes, and such other articles, as are displayed by grocery and other stores of various sorts, gasoline and oil service stations, and the like.

Another object more specifically is to provide a rack which is readily collapsible for shipment, 10 and which can be altered into its operative extended position, without requiring the use of tools of any sort, and which for the functions accomplished involves a minimum of expense to manufacture.

15 Still another object is to provide a rack, in which when in extended or operative position, supporting one or more cans, boxes, or other articles, for which it is adapted, such articles can be easily locked, both to prevent their theft, and to prevent them from becoming accidentally lost 20 while the rack and its contents are being transported from place to place.

A still further object is to provide in such a rack, common actuating means to effect the 25 functioning of the locking means for the contents of any or all shelves simultaneously, and conversely to provide for the release of the said shelf contents by a reverse functioning of such locking means.

30 And a still further object is to provide a rack of this type, which can also serve as a suitable support for any desired type of display advertising, or other medium, without in any way being dependent upon the other functions of the device, including said locking means.

With these and other objects in mind, the invention comprises further details of construction and operation, which are hereinafter fully brought out in the following description, when 40 read in conjunction with the accompanying drawing, in which Fig. 1 is a front elevation of a device comprising one embodiment of the invention; Fig. 2 is a vertical section on the line 2—2 of Fig. 1; Fig. 3 is a similar section of the 45 device, but showing the same in collapsed position for storage or shipping purposes; Figs. 4 and 5 are fragmentary horizontal sections on the lines 4—4 and 5—5, respectively, of Fig. 1; and Fig. 6 is a fragmentary vertical sectional 50 view of a portion of the device as shown in Fig. 2, but with a plurality of cans or boxes secured upon one of the shelves by the locking means.

Referring to the drawing, the device therein illustrated as comprising one embodiment of the 55 invention, consists in a pair of spaced, parallel,

upwardly extending members 1, to and between the uppermost end portions of which is secured a shelf 2, while spaced from and below said first shelf, any desired number of additional shelves 3 and 4 extend between and are pivotally secured 5 at 5 to said upright members.

The said shelves are preferably of different widths, and as shown in Figs. 4 and 5, comprise peripheral frame members 6, within which and extending longitudinally thereof, are positioned spaced ribs 7, which are preferably of less vertical extent than said frame members, said ribs being adapted to support cans, boxes, or other articles 8, which are prevented from direct lateral movement from upon said ribs by engagement 10 with the higher extending frame member.

Extending preferably parallel with, and longitudinally slidable with respect to, the upright members 1 are rods 9, which are connected together at their uppermost portions by a transversely extending locking member 10, which is adapted to perform the double function of supporting a sign or the like 11, if desired, and also in its lower position securing a can, box, or other article, upon the said uppermost shelf 2. Positioned at any desired distance above the shelves 3 and 4, additional locking members 12 extend transversely between the slidable rods 9, and are operative in their lowermost positions to similarly secure articles upon the respective shelves 3 15 and 4, positioned immediately therebeneath.

Pivottally connected at 13 to the upright members 1 are pairs of divergently downward extending legs 14, which in extended position operate to support the rack as a unit, and prevent its tilting or toppling over, either forwardly or rearwardly. To the lower portions of the legs of each pair are pivotally secured at 15, the respective sections 16 of a bottom shelf, which as a unit extends transversely between said pairs of legs, the adjacent portions of said bottom shelf sections being pivotally secured together at 17, and in their lowermost or extended position, said pivotally connected portions of said sections being directly engaged and supported by the inwardly directed hook-shaped end portions 18 of said upright members 1, as shown in Fig. 2.

Connecting the shelves 3 and 4, both together and to one of the sections 16 of said bottom shelf, is a link 19, which is preferably substantially parallel to the adjacent upright members 1, so that when the pivotally connected portions of the sections of said bottom shelf are raised, as shown in Fig. 3, said shelves 3 and 4 are simultaneously tilted angularly with respect to the upright sup- 45 50 55

porting members 1, in order that the rack as a unit, in such folded position, will occupy substantially less space when stored, or when being shipped.

5 Referring back to said locking means, there is an additional locking member 20 which extends between and is pivotally supported by the lower end portions of the rods 9, and in its lowermost position is operative to engage and secure larger 10 articles upon said bottom shelf when in operative extended position. The locking members 12 and 20 are pivotally secured to said rods in order that the former may tilt substantially in accordance with the tilting of the shelves next above them, 15 as shown in Fig. 3. The uppermost locking member 12 does not need to tilt, as the shelf 2 immediately thereabove also need not tilt, due to its relatively narrow front-to-rear extent.

It will be noted in Figs. 2 and 3, that the reciprocalation of the rods 9 is limited by the pins 21, carried by the upright members 1, being slideable within grooves 22, provided in said rods 9, or vice versa. It will also be noted that upon the inner or adjacent surfaces of said rods 9, there are secured angularly-shaped brackets 23, through the free apertured end portions of which extend the eccentrically positioned crank portions 24 of a shaft 25, which latter is journaled through the upright members 1, while extending loosely 30 through elongated apertures 26 in the rods 9, one end 27 of said shaft is preferably deflected angularly, so as to form a manually operable crank, and also a locking device.

As a crank, said end portion is manually movable 35 into the full-line position shown in Fig. 1, by which the crank portions 24 of the shaft 25 raise the brackets 23 and thereby the locking members 10, 12 and 20, into their inoperative positions with respect to the shelves immediately 40 beneath them, while the crank end of said shaft, when oscillated angularly into the dot-and-dash position 27a, operates to effect a lowering of the brackets 23 and rods 9, with a consequent depression of the locking members 10, 12 and 20, 45 with respect to whatever articles may be positioned upon the shelves immediately beneath them.

In order to lock the device against the theft or accidental loss of articles carried upon said 50 shelves, the crank end of the shaft may be fixed in its lowermost position, by securing it directly to an apertured bracket, or the like, 28 by any suitable means, such as a padlock, or other fastening means.

55 It is to be understood that, while one embodiment of the invention has been hereinbefore described, practically innumerable variations of the same may be made, which still fall within the scope of the appended claims.

60 Having thus described my invention, what I claim as new and desire to protect by Letters Patent of the United States is:—

1. A folding rack, comprising an upright member, a plurality of shelf members pivotally secured to said first member, means connecting said shelf members and operative to simultaneously change the angular relation of said shelf mem-

bers to said first member, means to secure articles upon each of said shelf members, and a reciprocatory rod slidably supported by said first member and pivotally supporting said securing means, whereby said securing means can also 5 change their angular relation with respect to said rod, to conform to the change in the angular position of said shelf members.

2. A folding rack, comprising an upright member, a plurality of shelf members pivotally secured to said first member, means connecting said shelf members and operative to simultaneously change the angular relation of said shelf members to said first member, a pair of angularly directed legs pivotally connected to said first member, and a sectional shelf the sections of which are pivotally connected together and also to the free end portions of said legs, and the pivotal connection between said shelf sections being pivotally connected to said first member, and one of said shelf sections being connected to said connecting means.

3. A folding rack, comprising an upright member, a plurality of shelf members pivotally secured to said first member, means connecting said shelf members and operative to simultaneously change the angular relation of said shelf members to said first member, a pair of angularly directed legs pivotally connected to said first member, and a sectional shelf the sections of which are pivotally connected together and also to the free end portions of said legs, and the pivotal connection between said shelf sections being pivotally connected to said first member, and one of said shelf sections being connected to said connecting means, the lower end portion of said first member engaging and limiting in one direction the movement of the pivotally connected portions of said shelf sections, and thereby cooperating in the support of said sectional shelf when in extended position.

4. A folding rack, comprising a pair of upright members, a plurality of shelf members pivotally secured to and extending between said first members, a pair of reciprocatory rods carried respectively by and slideable longitudinally with respect to said first members, locking elements connecting and extending between said rods and movable by said rods towards and away from said shelf members, and means operative to shift said rods and to actuate said locking elements, so as to secure articles upon a plurality of said shelves simultaneously.

5. A rack, comprising a pair of upright members, a plurality of shelf members secured to and extending between and in normally fixed relation with said first members, a pair of reciprocatory rods carried by and slideable longitudinally of said first members, locking means fixedly secured in parallel relation with and extending between said rods and movable by said rods towards and away from said shelf members, and rotatable means to shift said rods and to actuate said locking elements, so as to secure articles upon a plurality of said shelves simultaneously.

JONES S. JORDAN.
